UNITED STATES PATENT OFFICE.

MICHEL BODY, OF BRUSSELS, BELGIUM, ASSIGNOR TO OTTO MEURER, OF COLOGNE, GERMANY.

PROCESS OF COMBUSTION OF LIQUID HYDROCARBONS.

SPECIFICATION forming part of Letters Patent No. 630,282, dated August 1, 1899.

Application filed December 12, 1898. Serial No. 699,052. (No model.)

To all whom it may concern:

Be it known that I, MICHEL BODY, a subject of the King of Belgium, residing at Brussels, Belgium, have invented a new and useful Process and Means for the Combustion of Liquid Hydrocarbons, (for which patents have been applied for in Germany, No. 15,290, dated May 4, 1898; in France, No. 267,653, dated July 18, 1898, and in Italy, Rg. XXXIX, No. 6, dated June 10, 1898,) of which the following is a specification.

This invention relates to a process and means for the combustion of liquid hydrocarbons.

15 Liquid hydrocarbons, such as naphtha, &c., have generally only been successfully burned when atomized by injected air or steam, the spray formed being heated to a certain temperature. The flame developed thereby is 20 therefore more or less a thin flame of great intensity, which even the best chamotte stone can withstand for a short time only. This invention dispenses with the atomization of the liquid fuel and thereby obviates the disadvantages attending this method of firing. 25 It is based upon the principle that the hydrocarbon, instead of being atomized or vaporized, is decomposed in such a manner that it is for the most part converted into soot. This 30 is effected by igniting the liquid hydrocarbon and allowing it to burn with a small flame, so that a large quantity of soot is formed. This soot then forms an excellent combustible material containing a high percentage of carbon 35 in an exceedingly fine state of division. A furnace constructed upon this principle is illustrated in the accompanying drawings, in which—

Figure 1 is a longitudinal section of the furnace. Fig. 2 is a transverse section of the furnace, and Fig. 3 is a sectional plan.

In front of the heating-chamber proper, *a*, which is to be heated, there is arranged a fore-chamber *b*, of fireproof material, which is 45 heated red-hot by means of an auxiliary grate through the medium of ordinary solid fuel. In front of this fireplace, which is at once put out of operation when it has fulfilled its purpose of heating the brickwork, there is arranged a tray *c*, which is preferably made of 50 east-iron, the said tray being advantageously built in an opening in the brickwork or in the case of ships is mounted on a double suspen-

sion. This tray is in connection with the heated fore-chamber *b* and the liquid fuel to 55 be burned flows into the said tray from a vessel standing near the oven, boiler, &c. The shape of the tray is such that it is directed toward the liquid fuel, which flows laterally into it through the pipe *d*, not into the middle, but into the outer end thereof. When the tray is full, or practically so, the liquid fuel ignites and a considerable formation of soot takes place. This soot is by means of a steam-jet *g*, which is fitted in the space above 60 the tray, blown into the hot fore-chamber *b* for combustion. The steam-jet must be so directed that it does not enter the tray and disturb the liquid fuel. As soon as the soot passes into the hot chamber *b* it is burned, as 65 the air necessary for its combustion is introduced into the combustion-chamber simultaneously with the steam. The quantity of air drawn in can be easily adjusted by regulating the pressure at which the steam is injected. With this arrangement, therefore, 70 the hydrocarbon is not atomized or vaporized, but is decomposed, so as to form soot, carbon monoxid, and water. The soot and the carbon monoxid are then conveyed by the 75 steam-jet into the chamber *b*, where they are heated and completely burned with the aid of the air drawn in without the formation of an intense thin flame. The combustion is so complete that no smoke issues from the chimney. 80

Having now particularly described and ascertained the nature of my said invention and in what manner the same is to be performed, I declare that what I claim is—

1. The described process for burning liquid hydrocarbon such as petroleum residue, tar, and naphtha, &c., the same consisting in converting mainly into soot the hydrocarbon, mixing it with air and steam, and burning the 95 mixture in contact with a red-hot surface substantially as described.

2. In combination with the tray *c* pipe *d* and steam-pipe *g*, a fore-chamber *b* beyond such tray and pipes, and a heating-chamber *a* beyond such fore-chamber, all as shown and described.

MICHEL BODY.
